UNITED STATES PATENT OFFICE.

JOHN S. HOBSON, OF EDGEWOOD, PENNSYLVANIA, ASSIGNOR TO THE UNION SWITCH & SIGNAL COMPANY, OF SWISSVALE, PENNSYLVANIA, A CORPORATION OF PENNSYLVANIA.

CIRCUIT-CONTROLLER.

SPECIFICATION forming part of Letters Patent No. 722,301, dated March 10, 1903.

Application filed July 30, 1902. Serial No. 117,677. (No model.)

To all whom it may concern:

Be it known that I, JOHN S. HOBSON, of Edge-
wood, in the county of Allegheny and State
of Pennsylvania, have invented certain new
and useful Improvements in Circuit-Controllers,
of which the following is a specification.

My invention relates to circuit-controllers,
and especially to that type which is employed
to control the circuits of devices used for rail-
way switches and signals.

I will describe a circuit-controller embodying
my invention and then point out the
novel features thereof in the claims.

In the accompanying drawings, Figure 1 is
a top plan view of a circuit-controller embody-
ing my invention, the cover of a casing there-
for being removed. Fig. 2 is a view, partly
in vertical transverse section, taken on the
line 22 of Fig. 1 and partly in elevation. Fig.
3 is a top plan view, certain parts being broken
away. Fig. 4 is a section, the plane of sec-
tion being at right angles to Fig. 2, the cas-
ing and cover being removed. Fig. 5 is a
diagrammatic view of a circuit-controller em-
bodying my invention and the circuits con-
trolled thereby when operated by a sema-
phore. Fig. 6 is a detail sectional view of a
cam embodying my invention. Fig. 7 is a
diagrammatic view showing the connections
and points of contact of the circuit-controller.

Similar characters of reference designate
corresponding parts in all of the figures.

In the drawings, 2 designates a box, here
shown as being cylindrical, in which the cir-
cuit-controller mechanism is placed. It is
provided with a suitable cover 3, which may
be hinged, as shown at 4, to the box. The
cover is also suitably provided with adjust-
able fastenings and a suitable gasket 5, by
means of which dirt and foreign matter are
excluded from the box.

6 designates a stud centrally arranged in
the box 2, and 7 a disk carried by the stud
and, as here shown, integral with the stud.

45 The disk 7 is provided on one of its faces and
at its peripheral portion with a number of
teeth or serrations 8, which are preferably
radially arranged. The stud 6 is mounted in
a suitable bearing provided in the bottom of
50 the box, and it has fixed to it a lever-arm 13,

constituting an operating connection which
is adapted to be connected with any suitable
mechanism which will give it motion—as, for
example, a movable part comprised in either
a switch or signal mechanism.

55

9 and 10 designate cams. There may be
only one of such cams, or there may be more
than two, the number of the cams depending
upon the number of the circuits to be con-
trolled or the work required. Each cam is 60
provided with a tooth or teeth 12, which en-
gage with the teeth or serrations 8 of the
disk 7, and it is held on the disk 7 and from
any relative movement thereon by means of
its teeth and a screw 11. It will therefore be 65
seen that each cam is adjustable upon the
disk, and means are provided for locking the
cam in its adjusted position relatively to the
arm 13 and relatively to any other cam or
cams. As shown in the drawings, the ends 70
of the two cams overlap, and both cams are
secured to the disk 7 by means of a single
screw 11. A single screw may also be em-
ployed for securing a greater number of cams.
The operating-surface 9^a of each cam is at its 75
periphery, and inclines 9^b are provided at each
end of the said surface.

14 and 15 designate a pair of pins, here
shown as being oppositely arranged. Each
pin is secured to the box 2, and each pin 80
serves as a fulcrum or pivot for a rocking
part carrying arms or springs which are
moved into and out of contact with terminal
points or surfaces included in a circuit or
circuits. Obviously there may be any num- 85
ber of pins and rocking parts, according to
the number of circuits to be controlled or
other work required of the controller.

16 and 17 designate two rocking parts,
which for convenience may be termed "rock- 90
ers." The rocker 16 is fulcrumed on the pin
14, and the rocker 17 is fulcrumed on the pin
15. A pair of rollers 18 18^a are mounted in
the rocker 16, and a similar pair 19 19^a are
mounted in the rocker 17. To the rocker 16 95
are secured the metallic arms or springs 20
21, which are electrically insulated, as shown,
from the rocker and from each other, but
electrically connected to binding-posts 22 and
23 by strips or connections 24 25. The rocker 100

17 is similarly provided with metallic arms or springs 26 and 27, which are insulated from the rocker and from each other and are electrically connected by strips or connections 28 29 to binding-posts 30 and 31. The binding-posts 22, 23, 30, and 31 are insulated from their supporting-brackets 32 and 33, and these brackets are insulated from the box, as shown in Fig. 4. The bracket 32 is provided 10 with fixed surfaces or points 34, 35, and 36, which are included in a circuit or circuits, the surface or point 35 being common to both of the arms or springs 20 and 21. The other bracket 33 is provided with similar fixed surfaces or points 37, 38, and 39, which are included in a circuit or circuits, the surface or point 38 being common to both of the arms or springs 26 and 27.

The operation of the device is as follows:

- 20 The arm 13, which may derive its motion from any suitable mechanism common in devices to which I have described this instrument as being capable of use, is moved from the position shown in Fig. 1 in the direction 25 of the arrow. This causes the cam 9, which is normally in such position relatively to its rocker as to have one of the arms or springs in contact with the common fixed surface or point, to rotate by reason of the movement of 30 the stud 6 and the engagement of its tooth 12 with the teeth 8 of the disk 7. As the cam 9 passes out of engagement with the roller 18^a its inclined surface strikes the roller 18 of the rocker 16, and the arms or springs 20 and 35 21 are caused to move. The arm or spring 20 moves from the fixed surface or point 34 to the fixed contact 35, and the spring 21 moves from the fixed surface or point 35 to the fixed surface or point 36. In the form of 40 device herein described the continued movement of the arm 13 causes the cam 10 to leave the roller 19 and strike the roller 19^a and move the rocker-arm 17, thereby shifting the arms or springs 26 and 27. The arm or 45 spring 26 is moved from the fixed surface or point 37 to the fixed surface or point 38, and the arm or spring 27 is moved from the fixed surface or point 38 to the surface or point 39. The two cams may be so adjusted as to operate simultaneously. In some cases it would only be necessary to employ one cam, while in other cases more than two cams would be needed. These changes in the position of 55 the arms or springs may effect either the control of one or two circuits independently of one or two other circuits or cause the reversal of the direction of current from two electrical generators or reverse the current from one electrical generator and control two independent circuits as well, according to the work required of the mechanism. The two cams may be so adjusted as to operate simultaneously. In some cases it would only be necessary to employ one cam, while in other cases 60 more than two cams would be necessary to accomplish the work.

Fig. 5 shows the application of the circuit-

controller to a case where it is necessary that the cams have a fixed relation to each other and when the stroke required and the circuits to be controlled are known. In this figure, which is diagrammatic, the circuit-controller is used in connection with the operating mechanism of a railway semaphore signal apparatus provided with home and distant signal-arms and electrical circuits employed in connection therewith. *a* is a manually-operated signal apparatus having home and distant semaphore signal-arms, the home signal-arm *b* governing the entrance of trains to block C. *f* is a lever through the medium of which the signal-arm *b* is pulled to a position which may indicate "clear" when so permitted by an electric clutch *h*, and a train thus permitted to enter the block C. The lever *f* is here shown in its reverse position and coinciding with the reverse or clear position of the signal-arm *b*; but signal-arm *b* is shown in its normal or danger position, because a train is supposed to have passed signal apparatus *a* into block C, and thereby to have thrown signal-arm *b* to "danger" through the medium of the track-circuit and the clutch *h*, operated thereby. A connecting-rod *g* is shown connected at its upper end to the signal-arm *b* of signal apparatus *a* and at its lower end to the arm or lever 13 of the circuit-controller. The track-battery *m* has its terminals electrically connected to the rails of block-section C' through the medium of track-wire connections *n* and *n'* and the arms or springs 26 and 27, which are respectively in electrical contact therewith in such manner that when the lever 13 is in its normal position, as shown, the circuit from battery *m* flows through the rails of section C' in a given predetermined direction; but when the signal-arm *b* is lowered to its reverse or clear position, indicating track-section C to be clear, the lever 13 at the same time (through the medium of rod *g*) is lowered to its corresponding reverse position, and the arms or springs 26 and 27 are thereby made to change their relative positions of contact with the track connections *n* and *n'*, and consequently the current from track-battery *m* is made to flow through the rails of section C' in a direction the reverse of that maintained when the signal-arm *b* was in its danger position. Furthermore, with each and every movement of the signal-arm *b* from normal to reverse, and vice versa, the direction of the current from the battery *m* through the rails of section C' is reversed, and by each reversal of the direction of said current a movement is imparted to the polarized armature *p'* of the relay *r'*. These successive movements of the polarized armature *p'* alternately close and open a circuit *s'* at a point of contact *j*, which forms part of the circuit *s'*, and thus controls the movements of signal-arm *d'*, serving as a distant signal through the medium of the local or signal battery *t'* and the motor *v*. Thus when the home sig-

nal-arm *b* of block-section *C* is in its normal or danger position, as shown, the current from battery *m* flows through the circuit-controller and thence to the rails in such direction that 5 the resulting polarity of the relay-magnet *r'* will cause the polarized armature *p'* to open the circuit *s'* at the point of contact *j'*, thus depriving the motor *v* of electrical energy and allowing the distant signal-arm *d'* to assume 10 position indicating "caution," which it will do in the manner common to other railroad-signals by reason of the gravitation force of its counterweight. On the other hand, as soon as the signal-arm *b* is pulled into its reverse or clear position the direction of the 15 current from track-battery *m* through the rails will be reversed through the medium of the circuit-controller, and the polarized armature *p'* of relay *r'* is thereby caused to 20 close the circuit *s'* at the point of contact *j'*, and thus allow current from *t'* to flow through the motor *v*, thereby bringing the signal-arm *d'* into the clear position, provided the signal-arm *b'* is also clear, and the circuit-controller *x'* operated thereby consequently 25 closed.

In addition to performing the above-described operation the circuit-controller embodying my invention is made to open and 30 close the circuit *s*, as shown, an additional pair of arms or springs being provided, only one of which, however, is shown as being used. The arm or spring alternately opens and closes the circuit *s* at the point of contact 35 34 with each movement of the signal-arm *b* from "danger" to "clear," and vice versa, the point of contact 34 of the spring 20 being closed when signal-arm *b* is clear, thus allowing current to flow through the electric clutch *h'* and permitting the signal-arm *d* to be 40 cleared. When, however, the signal-arm *b* is at "danger," as shown, the point of contact 34 remains open, and the clutch-circuit *s* being thereby broken the distant signal-arm *d* cannot be cleared. It will be seen, 45 therefore, that each rocker and the arms or springs carried thereby in connection with the points or surfaces with which the arms or springs coact constitute means for controlling a circuit or circuits, and each of such means is independent of any other similar means. That each independent means may be operated from a common mechanism deriving motion from an extraneous source of 50 power and through a part or parts adjustable and comprised in the said mechanism each independent circuit means may be operated independently in any order simultaneously or in different combinations. The movements 55 given to the arms or springs are positive, and

the range of operation of the device is readily provided for by simple adjusting mechanism where it is necessary to employ it, or if the amount of movement required and conditions regarding the circuit are known the operating mechanism for shifting or moving the arms or springs need not be made adjustable. The operating-lever may be so placed as to work right or left and may project from either side of the box or casing, thereby providing 65 for all positions of the box with respect to the device by which it is operated.

It is obvious that the form and arrangement of parts may be varied and that the number of arms or springs on the brackets 14 and 15 70 75 may be changed by the skilled electrician without departing from the spirit and scope of my invention.

What I claim as my invention is—

1. In a circuit-controller, the combination 80 of means for controlling a circuit comprising a movable part, a disk and means by which it may be rotated, teeth or serrations provided on said disk and a cam adjustably mounted on the disk, engaging the teeth or 85 serrations to operate the movable part comprised in the circuit-controlling means.

2. In a circuit-controller, the combination 90 of means for controlling a circuit comprising a movable part, a disk and means by which it may be rotated, radially-arranged teeth or serrations provided on said disk, and a cam secured to the disk and having a tooth for engagement with the teeth on the disk for operating the movable part in the circuit-controlling means.

3. In a circuit-controller, the combination 95 of means for controlling a circuit comprising a rocking part, a disk provided with a number of radially-arranged teeth or serrations, 100 means for rotating it from an extraneous mechanism, and a cam adjustably carried by said disk and adapted to engage with the rocking part.

4. In a circuit-controller, the combination 105 of independent circuit-controlling means comprising arms and rockers which carry said arms, a disk and an operating connection, adjustable cams arranged on said disk for engaging rockers, and means for locking the 110 cams in fixed relation to each other and to said operating connection.

In testimony whereof I have signed my name to this specification in the presence of two subscribing witnesses.

JOHN S. HOBSON.
